UNITED STATES PATENT OFFICE.

EDWIN M. CLARK, OF CLARKSTON, MICHIGAN.

STORAGE TANK.

Application filed January 24, 1927. Serial No. 163,287.

My invention relates to storage tanks and particularly to a storage tank adapted for containing liquids of different specific gravities, as, for example water, and oil such as 5 crude oil, fuel oil, kerosene, gasoline, etc., hereinafter referred to as oil.

My invention has for its general object to provide novel and effective means for preventing losses of the oil by evaporation 10 while in storage, or at least minimizing the losses.

The special object of my present invention is to provide a tank that is hermetically sealed and such as will provide against the 15 presence of a space above the oil in which the vapors of evaporation would accumulate, and to provide for the expansion and contraction of the tanks contents as by natural changes in temperature while the 20 tank is hermetically sealed and without exposing the oil to the atmosphere.

Reference is to be had to the accompanying drawings forming a part of this specification, it being understood that the drawings 25 are merely illustrative of one example of the invention.

Figure 1 is a vertical section of an oil tank embodying my invention, parts being broken out for the purposes of the drawings;

30 Figure 2 is a detail in horizontal section as indicated by the line 2—2 of Figure 1;

Figure 3 is a view similar to Figure 1 showing a slight modification, the section line of Figure 3 being indicated by the line 35 3—3 in Figure 4 and

Figure 4 is a plan view of the tank shown in Figure 3.

In carrying out my invention in the form 40 shown in Figure 1, the tank 10 has a hermetic roof 11 as well as a water pipe 12 and an oil pipe 13 for the entrance and withdrawal of water and oil respectively. The tank 10 is extended above the roof 11 to form a water basin designated 110. Rising from 45 the roof 11 is a well 14 having a screw plug 15 distant from the top and engaging an internal thread in said well 14 the numeral 16 indicates the bottom of the tank.

In accordance with my invention I provide 50 a chamber 17 adjacent the roof 11 of the tank and said chamber communicates by a pipe 18 with the bottom of basin 110 and communicates by its upturned lower end with the bottom of chamber 17. Said pipe 15.

18 is disposed adjacent one end of the chamber 17. At the opposite end of chamber 17 is provided a curved pipe 19. Said pipe 19 communicates at one end with the top of chamber 17 and extends upwardly through the roof 11 and then downwardly 60 through said roof to communicate with the interior of the tank 10 beneath the roof. The pipe 19 constitutes in effect a spillway at that end of the chamber 17 for the purpose of permitting the overflow of liquid to the 65 tank 10.

A vent pipe 20 extends from the top of curved pipe 19 and is provided with a shut-off valve 21. The numeral 23 indicates a vertical shield extending downwardly from 70 roof 11 adjacent the pipe 19, and the numeral 24 indicates a similar shield depending from the roof 11 adjacent the oil pipe 13. The shield 23 forms a chamber leading to pipe 19 and the shield 24 forms a chamber leading 75 to the pipe 13 to direct oil to said pipe without undue disturbance of the contents of the tank, but it will readily be understood that the use of said shields is not absolutely necessary and they may be omitted.

In the use of the tank the water is initially 80 pumped into the roof basin 110 and passes downwardly through pipe 18, through chamber 17 and pipe 19 to the main tank where the water settles in the bottom to provide 85 a water cushion of the desired depth. The chamber 17 will remain filled with water. Oil is next pumped into the tank through pipe 13 until it reaches close to the roof. At this time the vent valve 21 is opened and the 90 well cover 15 removed. The pumping of the oil is continued until it issues from the vent 20, after which the vent is closed and the filling of the oil is continued until the oil rises in well 14 to the vane of the cover 15. 95 After the well cover 15 is replaced and the vent valve 21 closed water may be poured into the well 14 above the cover 15 to form a water seal. Water is now pumped into the basin 110 in the desired quantity.

The letter A indicates a body of oil in the tank; B, the water cushion at the bottom of the tank; C, the water in the tank 110; c, the water in the chamber 17; a, the limited quantity of oil above the water in the chamber 17; a a indicates the oil in the well 14 and D, the water seal in well 14 above cover 105

It will be observed that the chamber 17 is slightly inclined so that a cushion of water will always remain at that end adjacent the pipe 18 establishing connection between said chamber and the basin 110.

It will be obvious that a rise of temperature and the consequent expansion of the oil A will cause the oil to be forced through pipe 19 into the chamber 17, thereby 10 placing the water in said chamber 17 and causing said water to be forced through the pipe 18 to basin 110. The residue of water will remain in chamber 17, the amount depending upon the capacity of said chamber 15 to provide for the maximum expansion of the oil plus the presence of the water cushion in pipe 18. Manifestly the lowering of temperature and the consequent contraction of the oil content of the tank 10 will 20 result in the reversal of the described action.

In Figures 3 and 4 a slight modification is shown. The numeral 210 in said figure indicates the main tank; 110, the roof basin as previously described; 112, the water pipe; 25 113, the oil pipe; 111, the roof; 114, the well; 116, the bottom; 117, the chamber corresponding generally with the chamber 17; 118, the pipe establishing communication between the chamber 117 and the roof basin 110; 119, the curved pipe connecting chamber 117 with the tank 210; 120, the vent pipe; 121, the vent valve in said pipe 120; 220 indicates a funnel on pipe 121. Shields 23 and 24 are designated as in Figure 1 as 30 they have the same form and function as in Figure 1. The letter A indicates the body of oil in tank 210; B, the water cushion in the bottom of said tank; C, the water in the basin 110; c, the water in chamber 117 and 35 a, oil in chamber 117.

In the form shown in Figures 3 and 4 the chamber 117 connects at one end with basin 110 by curved pipe 118 and at the left said chamber communicates with tank 210 by the 40 pipe 119.

In the form shown in Figures 3 and 4 the pipe 119 is filled with oil to its apex by pouring the oil through the funnel 220 and pipe 120. Having in view the remote possibility of an air pocket being formed during the initial operation of filling the tank with oil and water, said air pocket would necessarily locate itself at the top of the pipe 119 and in such event an occasional opening for 45 a moment of the vent valve 121 will instantly correct and continuously insure against the presence of the air pocket.

The chamber 117 is indicated as approximately the area of the tank, but said chamber 50 may be smaller with good results.

It is to be observed that the main tank is 55 always filled with liquid and the fullness is insured by constant pressure from without.

The numeral 22 indicates a pipe for drain-

ing chamber 11 whenever necessary or desirable.

I would state furthermore that while the illustrated example constitutes a practical embodiment of my invention, I do not limit myself strictly to the exact details herein 70 illustrated, since, manifestly, the same can be considerably varied without departure from the spirit of the invention, as defined in the appended claims.

What I claim is:

1. In a structure of the class described a main oil tank having a roof, a water basin above said roof, a liquid holder within the tank, means connecting said tank at one end with said holder at the top of the holder and 80 means connecting said basin with said holder at the other end, at the bottom thereof.

2. In an oil storage tank, a main tank having a roof, a water basin above said roof, and a liquid holder within the tank, said 85 holder communicating at one point with the tank and communicating at another point with said basin and having a slight incline.

3. In an oil storage tank a main tank having a roof, a water basin above said tank, a 90 chamber in the tank near the roof, a pipe establishing communication with said chamber near one end and said basin, and a pipe establishing communication between said chamber near the opposite end and the interior of said tank near the roof; together with a vent pipe rising from said last mentioned connecting pipe.

4. In an oil storage tank a main tank having a roof, a water basin above said tank, a 100 chamber in the tank near the roof, a pipe establishing communication with said chamber near one end and said basin, and a pipe establishing communication between said chamber near the opposite end and the interior of said tank near the roof; together with a vent pipe rising from said last mentioned connecting pipe, and means to receive oil and conduct the same to said vent pipe.

5. In an oil storage tank, a main tank having a roof, a water basin above said roof, a chamber within the tank, said chamber communicating at one point with the tank and communicating at another point with said basin; together with a well rising from the roof of the tank and a closure for said well below the top thereof.

6. In an oil storage tank a main tank having a roof, a water basin above said tank, a chamber in the tank near the roof, a pipe establishing communication with said chamber near one end and said basin, a drain pipe leading from said first mentioned pipe, and a pipe establishing communication between said chamber near the opposite end and the interior of said tank near the roof.

EDWIN M. CLARK.
